(57) **CLAIM**

We claim the ornamental design for a pipe fitting, as shown and described.

DESCRIPTION

FIG. 1 is a front view of a pipe fitting of the design according to this invention.

FIG. 2 is a back view of the pipe fitting of the design according to this invention.

FIG. 3 is a right side view of the pipe fitting of the design according to this invention.

FIG. 4 is a left side view of the pipe fitting of the design according to this invention.

FIG. 5 is a top view of the pipe fitting of the design according to this invention; and,

FIG. 6 is a bottom view of the pipe fitting of the design according to this invention.

The broken lines shown in the drawings are for illustrative purposes only and form no part of the claimed design.
